UNITED STATES PATENT OFFICE.

JAMES E. GREATHOUSE, OF MABANK, TEXAS.

CENTER FOOT FOR CULTIVATORS.

SPECIFICATION forming part of Letters Patent No. 674,405, dated May 21, 1901.

Application filed January 14, 1901. Serial No. 43,218. No model.

To all whom it may concern:

Be it known that I, JAMES E. GREATHOUSE, a citizen of the United States, residing at Mabank, in the county of Kaufman and State 5 of Texas, have invented a new and useful Center Foot for Cultivators, of which the following is a specification.

My invention is an improved center foot or standard for a cultivator, the object of my 10 invention being to provide an improved center foot or standard which is adapted to be readily attached to and detached from a beam or beams of a cultivator adjusted thereon and adapted for the attachment of a shovel, plow, 15 or sweep of any kind required.

My invention consists in the peculiar construction and combination of devices hereinafter described and claimed.

In the accompanying drawings, Figure 1 is 20 a perspective view of one of my improved center feet or standards, showing the same attached to the beams of a cultivator. Fig. 2 is a detail perspective view of my improved center foot or standard.

25 My improved center foot or standard is substantially V-shaped and is formed from a steel or iron rod of suitable length and diameter, bent at the center, as at 1, to form the upwardly-diverging arms 2. The central 30 lower end of the foot or standard is curved forward, as shown, and disposed at a suitable angle to form a rest against which the rear side of the cultivator, shovel, plow, or sweep bears and to dispose said cultivator, shovel, plow, or sweep at the requisite inclination. The central portion 1 is semicircular in form, as shown, to form a longitudinal slot 3, the arms 2 being secured together at a suitable distance above the lower curved 35 central portion 1 by a cross-bar 4, which is welded thereto and closes the upper end of the slot 3. The upper portions of the arms 2 are parallel to each other, and when the center foot or standard is in operative position 40 the said upper portions 5 of the arms thereof are vertical. Each of the said arms 2 is provided with a collar 6, adjustable thereon and provided with a set-screw 7.

The shovel, plow, or sweep, which, as before stated, may be of any form, is secured to 50 the center foot or standard by a bolt 8, which passes through and is adjustable in the slot 3. In order to secure the center foot or standard to the beams of a cultivator, the vertical upper extensions 5 of the arms 2 of the 55 center foot or standard are passed through the eyes or eyebolts 9, which serve to clamp the same to the beams, the said eyebolts and the said vertical upper extensions of the arms of the center foot or standard adapting 60 the latter to be secured at any desired adjustment to the beams. The collars 6 bear on the eyebolts, as shown, and prevent the center foot or standard from becoming disengaged from the eyebolts when the beam is 65 raised.

My improved center foot or standard may be attached to the beam or beams of a cultivator in any other suitable manner and by any other suitable means, if preferred, and I 70 do not limit myself in this particular.

In Fig. 1 of the drawings my improved center foot or standard is shown attached to and disposed between two beams, one of the latter, for the sake of clearness of illustration, 75 being indicated by dotted lines; but it will be understood that my improved center foot may be secured to a single beam, if desired.

Having thus described my invention, I 80 claim—

A center foot or standard of the class described comprising a metallic bar bent to form the upward diverging arms 2 and the slot 3 between the said arms at the lower end of said center foot or standard, in combination with eyebolts and collars on the upper portions of said arms 2, said collars having set-screws, substantially as described.

In testimony that I claim the foregoing as my own I have hereto affixed my signature in 90 the presence of two witnesses.

JAMES E. GREATHOUSE.
